UNITED STATES PATENT OFFICE.

WILLIAM S. ELTERS, OF DAYTON, OHIO, ASSIGNOR OF ONE-HALF TO THEODORE H. BARLOW, OF DAYTON, OHIO.

PEG-LEG.

1,257,284.

Specification of Letters Patent. Patented Feb. 19, 1918.

Application filed October 4, 1917. Serial No. 194,704.

To all whom it may concern:

Be it known that WILLIAM S. ELTERS, a citizen of the United States, residing at Dayton, in the county of Montgomery and State of Ohio, has invented certain new and useful Improvements in Peg-Legs, of which the following is a specification.

This invention relates to new and useful improvements in artificial limbs of the peg-leg type. One object of the invention is to provide a device of this type which is of sufficient strength but of exceedingly light weight, and another object of the invention is to provide a device of this type which possesses a certain amount of flexibility thereby giving comfort to the wearer.

Referring to the accompanying drawings, Figure 1 is a side elevation. Fig. 2 is a front elevation. Fig. 3 is a section on the line 3—3 of Fig. 1. Fig. 4 is a section on the line 4—4 of Fig. 3 and Fig. 5 is a section on the line 5—5 of Fig. 4.

Referring more particularly to the drawings, 1 represents a semi-cylindrical saddle which is provided with a pad 2. The saddle 1 is adapted to receive the knee of the wearer, it being understood that the leg is adapted to be used by those persons whose leg is amputated below the knee. Extending downwardly from the saddle 1 is the peg or leg of the device 3. At its lower end the peg 3 is provided with a foot 4 which may be soled with leather 5. The peg 3 is tubular, is formed of sheet metal and is provided with corrugations 6. The peg 3 is, therefore, of light weight and possesses great strength. The device is attached to the leg and body of the person by the following means: Extending upwardly from the saddle 1 is a short arm 7 and a longer waist arm 8 both of which are formed of sheet metal the longitudinal edges of which are corrugated or provided with beads 9 which strengthen said arms. The arms 7 and 8 so provided with tubular beads 9 which are flattened as at 10 where they are attached to the side of the saddle 1. This form of connection permits of a certain amount of flexibility between the arms and the lower portion of the device. The upper end of the arm 8 is provided with a loop 11 and this arm extends to the waist of the wearer where it may be attached to his body by means of a belt (not shown).

The loop 11 is so shaped as to form a handle which permits the upper part of the device to be grasped by the hand thereby forming a support for the upper portions of the body. The arms 7 and 8 are connected by a resilient yoke 12 which passes in front of the leg above the knee, it being understood that the knee rests upon the pad 2 in the saddle 1. The flexible connection between the arm 8 and the lower portion of the device is strengthened by a resilient brace 13 which is connected to the peg at 14 and to the arm 8 at 15 and at 16 through the aid of a post 17. The extreme upper end of the device, as before stated, is connected to the body of the wearer by the belt referred to, while the leg of the wearer is secured to the device by straps 18 and 19. The strap 18 is attached to the arms 7 and 8 and passes in the rear of the leg above the knee while the straps 19 are attached to the rear end of the saddle 1 and extend above the leg below the knee. It is to be understood that the stump of the amputated leg will extend beyond the saddle 1, therefore, the device may be used by one whose leg has been amputated before the stump has entirely healed. A peg-leg as thus constructed may be made entirely from sheet metal which permits the same to be made flexible and of extreme light weight, thereby giving comfort to the wearer.

Having described my invention, I claim:

1. A device of the character specified comprising a tubular peg-leg constructed of corrugated sheet metal, a knee saddle mounted thereon, arms extending from opposite sides of said saddle said arms being formed of corrugated metal and one of which extends to the waist of the wearer, and a resilient yoke connecting said arms above the saddle.

2. In a peg-leg, a saddle adapted to support the knee, a peg-leg extending from said saddle and formed of corrugated sheet metal, a waist arm and a short arm extending from said saddle and formed of corrugated sheet metal, a yoke connecting said arms above the saddle, and a resilient brace connection between the waist arm and the peg-leg.

In testimony whereof I affix my signature.

WILLIAM S. ELTERS.
